UNITED STATES PATENT OFFICE.

ALBERT T. MANCHESTER, OF NORTH PROVIDENCE, RHODE ISLAND.

DESIGN FOR THE FRAME OF A CHILD'S VEHICLE.

50,394.

Specification for Design.

Patented Feb. 27, 1917.

Application filed July 28, 1916. Serial No. 111,950. Term of patent 7 years.

To all whom it may concern:

Be it known that I, ALBERT T. MANCHESTER, a citizen of the United States, residing at North Providence, in the county of Providence and State of Rhode Island, have invented a new, original, and ornamental Design for the Frame of a Child's Vehicle, of which the following is a specification, reference being had to the accompanying drawing, forming part thereof.

The figure is a perspective view showing my new design for the frame of a child's vehicle.

I claim:

The ornamental design for the frame of a child's vehicle, as shown.

ALBERT T. MANCHESTER.

Witnesses:

HARRY C. OWEN,
JOHN W. SLATER.
